UNITED STATES PATENT OFFICE.

ERNEST B. FAHNESTOCK, OF NEW YORK, N. Y.

COMBINATION LIGHTNING-ARRESTER AND FUSE-BLOCK.

1,010,606.

Specification of Letters Patent.

Patented Dec. 5, 1911.

Application filed February 19, 1907. Serial No. 358,168.

To all whom it may concern:

Be it known that I, ERNEST B. FAHNESTOCK, a citizen of the United States, and resident of the borough of Manhattan, city, county, and State of New York, have invented certain new and useful Improvements in Combination Lightning-Arresters and Fuse-Blocks, of which the following is a specification accompanied by drawings.

10 This invention relates to fuse blocks which are preferably used in combination with a lightning arrester for protecting telephones and other electrical instruments from damage by lightning or other heavy currents, but 15 the invention may be utilized in any connection in which it is found applicable.

The objects of the invention are to secure a construction of combination lightning arrester and fuse block in which the fuses are 20 readily removable and the wire connections thereto made easily and which permits of a cheap and easy method of construction.

Another object of the invention which applies particularly to telephone uses when the 25 device is used for the protection of a subscriber's telephone, is to provide a construction which reduces the number of possible loose connections in the telephone circuit to a minimum.

30 Further objects of the invention will hereinafter appear, and to these ends the invention consists of a device for carrying out the above objects embodying the features of construction, combinations of elements, and 35 arrangement of parts having the general mode of operation substantially as herein-after fully described and claimed in this specification and shown in the accompanying drawings, in which;

40 Figure 1 is a plan view of a combination lightning arrester and fuse block embodying the invention; Fig. 2 is a side elevation of the invention; Fig. 3 is a detail vertical sectional view on the line 2-2 of Fig. 1; Fig. 45 4 is a detail sectional view of one of the tubular fuses.

Referring to the drawings, A represents a support which may be a board, preferably covered with fireproof material B, as for 50 instance, asbestos. On this support A is suitably secured a base C of insulating material, preferably porcelain, which carries the apparatus of the lightning arrester, and also serves as a support for the tubular fuses 55 D. The tubular fuse D comprises the fuse

wire E inclosed in a tube F of insulating material, as for instance papier mâché, and suitable means are provided for including the fuse wire E in the electric circuit.

The apparatus of the lightning arrester 60 portion of the device is not shown in detail because any suitable form of apparatus may be used which is located beneath a suitable metallic cap G secured to the base C. The insulating base C in this instance is provided 65 with upright projections H, forming supports for the tubular fuses, and as shown, each projection is provided with a hole or aperture for the reception of one end of the tubular fuse, although any other suitable 70 form of support may be provided by means of which the tubular fuse is supported throughout any portion of its length instead of at the extreme end.

The fuse wires E are adapted to be connected in the line circuit, while the lightning arrester portion of the device is adapted to be bridged across the line, and is provided 75 with a ground connection.

In apparatus of the type described as heretofore constructed, means have been provided for holding or supporting the tubular fuse at both ends, and for electrically connecting the fuse with said supports, said supports for the fuse being then provided 80 with binding posts or other means for connecting the conducting wires thereto. In accordance with the present invention, the entire support at one end of the fuse is done away with, and means are provided for connecting the conducting wire directly to the end of the fuse without the intervention of any intermediate support. The advantages 85 of this construction are many, and reside in the fact that the cost of construction is greatly cheapened by doing away with one entire support, and also reducing to a minimum the number of possible loose connections in the circuit, which is particularly desirable in telephone circuits. In the old 90 construction in which a support was used for the end of the fuse, a loose connection might occur between the wire and the binding post, between the binding post and the support and between the support and the fuse, while according to the present construction but one possible chance for a loose 95 connection occurs, and that is between the wire and the binding post, but this possibility is reduced to a minimum by utilizing 100 105 110 115

an improved spring binding post P constructed in accordance with United States Patent Reissue No. 12642, granted April 23, 1907, to which I have permission to refer, although the invention is not limited to the use of this particular binding post. This binding post P comprises the body member a, a spring member b, and the retaining portion or resistant member c, which is adapted 10 to coöperate with the spring member b to clamp a conductor between said members. In the construction shown, the spring member b is provided with a slot, which is adapted to inclose the resistant member c, and in 15 the operation of the device the spring member is forced toward the resistant member and the conducting wire is inserted in the angles of said members, and is retained in position therein by the retractive force of 20 the spring member.

The tubular fuse is provided at each end with metallic connectors, preferably in the form of plugs, having holes I extending therethrough in which the ends of the fuse 25 wire E are soldered or otherwise connected. One of these plugs J is preferably provided with a screw threaded tip K, by means of which the fuse may be secured in the support H, while the other plug L is preferably 30 provided with a projecting portion O, by means of which the spring clip P may be secured thereto. In this instance the base of the spring clip is preferably provided 35 with an aperture which is placed over the projection O, and the head of the projection is then upset to hold the spring clip in place. The plugs J and L are preferably secured in the tube F as by means of the pins Q. The tubular casing F is preferably 40 provided with vent holes R on its under side, and means are provided for insuring that these vent holes shall project downwardly toward the fireproof material B when the fuse is in position in the support 45 H. Any suitable means may be provided for this purpose, and I have constructed the screw-threaded tip K with a flat side S adapted to enter a corresponding aperture T having a flat side provided in the angular 50 connector U which lies against the face of the support H and also extends horizontally along the base C. The aperture T falls opposite the hole in the support H so that when the tubular fuse is inserted in the sup- 55 port the vent holes R lie on the under portion of the fuse and project toward the fireproof material B. The screw-threaded tip K projects through the aperture T in the connector U and is adapted to receive a 60 binding nut V or other suitable device for retaining the fuse in position.

Suitable plates or connectors W extend along the top of the base C beneath the cap G, and electrically connect with the apparatus of the lightning arrester, and spring

binding posts P are arranged in electrical connection with the angular connectors U and the connectors W. In this instance the body members a of the spring binding posts P are arranged between the connectors W 70 and U and held in position by the screws X countersunk in the under portion of the base C. A connector Y extending along the top of the base C also connects electrically with the apparatus of the lightning arrester, and another spring binding post P is secured in electrical connection with the connector Y as by means of the screw X countersunk in the under portion of the base C. The line wires are connected to the binding posts P at the free ends of the tubular fuses, and to the binding posts P at each side of the lightning arrester apparatus, while a ground connection is made with the binding post P on the connector Y which 80 leads to the lightning arrester.

The operation of the apparatus is like that of devices of this type in which a high potential breaks through the dielectric in the lightning arrester and discharges to the 90 ground.

According to this construction the tubular fuse may be readily removed from the apparatus or adjusted therein by simply removing the nut V and withdrawing the fuse, and the fuse cannot be replaced in the support H in any other position than with the vent slots R projecting downwardly which insures that the discharge from the rupture of the fuse will be against the fireproof material B and not in any other direction. The tubular fuse in itself forms an improved article of manufacture which may be applied in a number of different ways to apparatus of the type described or 105 analogous apparatus. The tubular fuse may also be used in connection with ordinary fuse blocks, in which case, it may, if desired, be provided with a spring binding post at each end.

Obviously some features of this invention may be used without others and the invention may be embodied in widely varying forms.

Therefore, without limiting the invention 115 to the devices shown and described, and without enumerating equivalents, I claim and desire to obtain by Letters Patent the following:

1. The combination of a base, a lightning 120 arrester mounted thereon, a support on said base, and a tubular fuse having one end free and unsupported and the other end mounted on said support and in electrical connection with the apparatus of the lightning arrester, said unsupported free end of the fuse being provided with means for attaching to it directly an electric conductor.

2. The combination of a base, an electrical 125 device mounted thereon, a support on said 130

base, and a tubular fuse having one end free and unsupported and the other end mounted on said support and in electrical connection with the apparatus of the electrical device, said unsupported free end of the fuse being provided with means for attaching to it directly an electrical conductor.

In testimony whereof I have signed this specification in the presence of two subscribing witnesses:

ERNEST B. FAHNESTOCK.
